MECHANICALLY OPERATED VALVE APPARATUS

Filed June 1, 1928

Inventor:
John T. Janette
By: Glenn S. Noble, P.H.

UNITED STATES PATENT OFFICE

JOHN T. JANETTE, OF CHICAGO, ILLINOIS

MECHANICALLY-OPERATED VALVE APPARATUS

Application filed June 1, 1928. Serial No. 282,236.

This invention relates to power or motor operated means for actuating valves, and more particularly to devices of this character having the valve held in normally closed position and opened automatically under predetermined operating conditions. A particular illustration of the utility of this apparatus is its use in connection with the operation of combustion apparatus and more particularly gas fired furnaces.

In apparatus of this character it has been found desirable to use blowers for supplying air instead of depending upon natural draft. These blowers are operated by means of motors and the gas is conducted through suitable piping to a magazine chamber where it is mixed with the air preparatory for combustion. In order to prevent the escape of gas when the motor is not running and to prevent gas from passing to the burner when there is not sufficient air supply furnished by the blower, I provide the novel valve and actuating mechanism forming one of the principal features of this invention.

In accordance with my improved apparatus, I provide a valve which is normally held closed by means of a spring or the like and provide mechanical means actuated by the motor for opening the valve when the motor has reached a predetermined speed.

As above indicated, the objects of this invention are to provide an improved valve with mechanical means for automatically opening the same; to provide a valve having resilient means for holding the same in closed position and governor actuated means for opening the valve under predetermined conditions; to provide a gas furnace apparatus having a blower for furnishing air and a valve for controlling the supply of gas and automatic mechanical means for opening the valve when the motor reaches a predetermined speed; and to provide such other advantages and improvements as will be described more fully hereinafter.

In the accompanying drawings illustrating this invention,

Figure 1 is a side view of a gas burner apparatus including my improved valve;

Figure 2 is an enlarged longitudinal sec-

tional view of the valve showing its mounting on the motor;

Figure 3 is a sectional view taken on the line 3—3 of Figure 2; and

Figure 4 is a sectional view taken on the line 4—4 of Figure 2.

As shown in these drawings, 5 represents a motor of any suitable character which drives a blower 6 having an outlet pipe 7 leading to a burner or magazine chamber 8, these parts being all of more or less standard or well known construction. A gas or fuel supply pipe 9 is connected to the inlet of a valve casing 10 by means of a hollow plug or connection 11. The valve casing 10 has an inlet opening 12 which is provided with a valve seat 13. The valve disk or valve proper 14 is carried on a stem 15 which is slidably mounted in a bearing 16 which is carried by arms 17 in the plug or connection 11. The valve is preferably provided with a facing or engaging disk 18 of resilient or fibrous material suitable for making a tight closure against a valve seat.

The valve casing is provided with an outlet 19 which is connected by a pipe 20 with the burner or mixing chamber 8. The valve casing 10 is secured to the motor 5 by means of a flanged coupling 21. This coupling is secured at one end of the motor and is provided at the other end with a transverse wall or closure 22 having a bearing 23 for the motor shaft 24. This bearing is provided with a stuffing box 25 to prevent the escape of gas or fuel from the valve chamber.

The motor shaft is provided with centrifugal opening means located within the valve body for opening the valve. In the particular arrangement shown, the shaft is provided with a substantially cup-shaped annular support 26 which is secured thereto in any suitable manner, as by means of a set screw 27. Bell crank governor levers 28 are pivoted at 29 to the disk or support 26, their outer legs forming the governor weights and their inwardly projecting legs being provided with balls or bearings 30 which engage with a groove or slot 31 in a head formed on a sleeve 32, which sleeve is slidably mounted on the motor shaft 24. A washer or retaining

ring 33 fits over the sleeve 32 and is provided with oppositely disposed projections which are engaged by springs 34 on screws or studs 35 which engage with the cup or support 26. These springs tend to hold the governor in normal position with the weights adjacent to the collar as shown in Figure 2. The governor levers 28 are also preferably provided with projections 36 which are adapted to engage with the collar or support 26 to limit the opening movement of the governor.

The sleeve 32 is provided at its outer end with a ball 37 which engages with a disk or washer 38 and which is adapted to engage with the valve for opening the same. Instead of having the ball engage directly with the valve, I prefer to provide a wearing disk or plate 39 which is secured in a guide 40 on the valve, which guide engages with the inlet opening 12.

When the device is used in connection with a gas fired furnace, the gas in the pipe 9 which is, of course, more or less under pressure is normally prevented from passing to the burner by the valve which is normally closed. When the motor is started and air is being delivered to the burner, the centrifugal opening device will open the valve as soon as the motor has reached a predetermined speed and will admit gas to the burner. It will thus be seen that the valve is mechanically opened and in the event of any failure of current to the motor, or if the motor stops for any reason, the valve will immediately close, thereby guaranteeing safety of operation in this respect. It will also be noted that the centrifugal governing or opening mechanism which is revolved in the valve chamber will act in the nature of a propeller whereby there is a tendency to suck the gas or fuel in through the intake orifice and force it through the outlet as in a centrifugal fan. This is a particularly beneficial feature in the event of the lowering of the pressure in the gas mains as it tends to provide a constant and sufficient supply of gas to the burner. This centrifugal action also tends to prevent escape of gas through the motor shaft bearing if the bearing is not sufficiently tight inasmuch as there is a tendency to create a suction through the bearing.

Changes may be made in the arrangement of the parts and in the details of construction in order to adapt the device for different purposes or for different conditions; therefore I do not wish to be limited to the exact arrangement or construction herein shown and described, except as specified in the following claims, in which I claim:

1. The combination of a valve body having an inlet and an outlet and provided with a valve seat, a valve for engagement with said seat, a spring tending to hold said valve in closed position, a shaft projecting into the valve body, a bearing for said shaft, a cup

mounted on said shaft, lever arms pivotally mounted to said cup and having inwardly extending projections, a sleeve adapted to be reciprocated by said inwardly extending projections, yielding means for holding the sleeve in normal position, a ball carried by said sleeve and adapted to coat with the valve for opening the same, the arrangement being such that when the shaft is rotated at a proper speed the lever arms will swing outwardly and cause the sleeve and coating parts to open the valve.

2. In an apparatus of the character set forth, the combination of a burner, a motor, a fan actuated by the motor, a conduit from the fan to the burner, a valve having a closed body mounted on the motor, an intake pipe for said valve, an outlet pipe from the valve to the burner, means tending to hold the valve in normally closed position, and centrifugally actuated means mounted on the motor shaft within the valve body for opening the valve when the motor reaches a predetermined speed.

3. In a gas combustion apparatus, the combination of a burner, a motor, a fan actuated by the motor, a conduit from the fan to the burner, a valve having a closed body, an inlet from a source of gas supply to the valve, an outlet passageway from the valve to the burner, means tending to hold the valve in closed position, centrifugally actuated means within the valve body for opening the valve and a connection from the motor to said means for turning the same, the arrangement being such that the valve will be opened when the motor reaches a predetermined speed.
